United States Patent Office.

JOHN THOMAS JONES, OF NEW YORK, N. Y., ASSIGNOR TO THE
SINGER MANUFACTURING COMPANY.

Letters Patent No. 86,164, dated January 26, 1869.

IMPROVEMENT IN SEWING-MACHINES.

The Schedule referred to in these Letters Patent and making part of the same.

To all whom it may concern:

Be it known that I, JOHN THOMAS JONES, of the city, county, and State of New York, have invented certain new and useful Improvements in Sewing-Machines; and that the following is a full, clear, and exact description and specification of my said invention.

My invention consists of certain improvements in the construction of sewing-machines. These constitute parts of my invention, and may be used severally or collectively, as circumstances render expedient.

My first improvement relates to the means for driving a transverse shuttle, by which I mean a shuttle moving transversely to the line of feed; and its object is to operate said shuttle from the driving-shaft of the needle, or some other shaft that is parallel with the shuttle-race, or thereabouts, in a simple manner, and without the use of counter-shafts or gearing. This improvement consists of the combination of the shuttle-driver with the driving-shaft of the needle, by means of a bell-crank, vibrating in the plane of the said shaft, and a connecting-rod, operating upon ball-crank pins, secured to the driving-shaft and bell-crank, so that the rod adapts itself to the variation in the relative positions of the two crank-pins.

The object of the next improvement is to permit a reciprocating feed-bar to be readily changed, so that feed-bars, having feeding-surfaces of different qualities, can be used in the machine, as required by the work. This improvement consists of the combination of the feed-bar with its driver, by means of a fork and rocking tooth, and covering said feed-bar by a sliding plate, so that, by simply moving said sliding plate, the feed-bar may be disconnected from its driver simply by lifting it, and consequently one feed-bar can be readily removed from the machine, and another dropped into its place.

The object of the next part of my invention is to cause the feed-bar to be moved positively (without the action of a spring) in both directions, with intervals of rest between its movements; and it consists of the combination of the feed-bar with the revolving shaft that drives it, by means of a triangular cam, working in a quadrangular ring-frame, applied to the end of the connecting-rod that transmits motion to the feed-bar.

The object of the next improvement is to enable the feed-bar, while moved positively in both directions, to be adjusted to vary the length of motion of the feed-bar, and consequently the length of the feed. It consists of the combination of the feed-bar with the rotating shaft that drives it, through the intervention of a cam, operating in a ring-frame, and a pin, sliding in a slot in a rocking arm, to which said cam imparts motion, so that while the cam imparts a positive motion to the feed-bar in both directions, the extent of that motion may be varied by varying the position of the pin in the slot of the rocking arm.

The object of the next improvement is to prevent

excessive wear between the feed-bar and the instrument for raising and lowering it, and consists of the combination of the feed-bar with a rocking cam for lifting it, which can be so operated as to remain at rest, or thereabouts, while the feed-bar is reciprocating, and is constructed with a flat side, which presents a broad, flat surface for the feed-bar to slide upon.

The object of the next part of my invention is to permit the presser-foot to be turned horizontally, without the necessity of disconnecting it from its shank, and consists of the combination of a round presser-foot shank with a guiding slide, by means of a pin and notch, or their equivalents, which permit the shank and presser-foot to be readily turned by hand, but hold them in their proper positions during the operations of the machine.

In order that my invention may be fully understood, I have represented, in the accompanying drawings, a sewing-machine which embodies all parts of my invention, and I will proceed to describe it.

Figure 1 represents a view of the machine, with certain parts removed, to permit the residue to be seen;

Figure 2 represents a top view of the machine, with the plate of the bed and the parts above it removed;

Figure 3 represents a vertical transverse section of the machine at the line *x x* of fig. 1;

Figure 4 represents a fragmentary side view of the machine;

Figure 5 represents a transverse section of parts of the machine at the line *y y* of fig. 1;

Figure 6 represents a rear view of certain parts of the machine;

Figure 7 represents a top view of parts of the machine;

Figure 8 represents a front view of a portion of the needle-arm, and the adjacent parts;

Figure 9 represents a section of the wheel presser-foot through the axis of the arm on which the wheel rotates; and

Figure 10 represents a view of a flat presser-foot fitted to be used on the machine.

The first six of said figures are drawn upon a scale of half the working dimensions. The last four figures represent the parts of the working size.

The bed-plate A of the machine is supported upon a table, B, and is connected with it by hinges, which permit the machine to be turned up edgewise, for examination, and for other purposes.

The needle *a* of the machine is carried by a sliding needle-bar, C, to which motion is imparted, as in the ordinary Singer sewing-machine, by means of a rotating driving-shaft, D, which traverses the needle-arm E longitudinally, and is fitted, at its front end, with a crank-pin, which works in a cam-plate, secured to the needle-bar, the crank-pin being fitted with a friction-wheel, as is usual in such cases.

The driving-shaft D is fitted, at its rear end, with a

fly-wheel, F, and with a grooved belt-pulley, G, to which motion is imparted by a driving-belt, H, in the usual manner.

The driving-belt is conducted downwards to a treadle-motion beneath the machine, and the part of the belt above the table is protected by a cover, K.

In order that the machine may embody the first of my invention, this cover K is made fast to the bed-plate A of the machine, instead, as heretofore, to the table of the treadle-motion; hence the cover does not require to be removed when the machine is turned up from the table B, but comes up with the machine, thereby saving the trouble of unscrewing it, and replacing it afterward.

The shuttle I of the machine is constructed to traverse in a shuttle-race, L, whose direction is transverse to the line of the feed, and parallel with the line of the needle-arm E, and with the axis of the driving-shaft D.

In order that the next part of my invention may be embodied in the machine, the shuttle-driver J is connected by a rod, b, with one of the arms c of a bell-crank, M, and the other arm c', of said bell-crank, is connected by a rod, b', with the crank d of the driving-shaft D.

The plane of vibration of the bell-crank is in the axis of the driving-shaft, or thereabouts, and is consequently perpendicular to the plane of revolution of the crank d of that shaft, and in order that the connecting-rod b', between the crank and bell-crank, may accommodate itself to this peculiarity of arrangement, the crank-pin of the crank d, and the pin of the arm c' of the bell-crank, are made of ball-form, as represented in dotted lines in fig. 1, and the stub-ends e e' of the connecting-rod b', are of corresponding form internally, so that the connecting-rod can swivel upon the pins.

The machine is provided with a reciprocating rough-surfaced feed-mechanism, and in order that the next part of my invention may be embodied in the machine, the feed-bar N, or feed-dog, as it is sometimes called, is constructed with a fork, g, at its under side, which fits loosely upon the end or tooth h of a reciprocating arm or driver, f, by which motion is imparted to the feed-bar, so that the feed-bar lies loosely upon the driver, and can be readily lifted from it.

Moreover, the said slot is closed by a cover or slide, O, which covers the feed-bar up to the aperture in the throat-plate j, through which the end of the feed-bar rises, so that the removal of this cover leaves the feed-bar free to be lifted out of the machine.

In order that the next part of my invention may be embodied in the machine, the feed-bar is caused to reciprocate in the line of the feed by the rocking of the driver f, which projects from a rock-shaft, P, and to which motion is transmitted from the driving-shaft D, through a cam, Q, a connecting-rod, R, a counter rock-shaft, P', a connecting-rod, R', and the arms k k' k'', secured to said rock-shaft.

The cam Q (see Figure 3^a) is triangular, with the apex nearest the shaft, and it works in a quadrangular ring, S, formed upon the upper end of the connecting-rod R, the effect of this construction being to leave the connecting-rod R and its connections, including the feed-bar N, practically stationary at the extremes of its stroke, and as the connection between the feed-bar and the driving-shaft is never broken nor intermittent, and no spring is required to cause the feed-bar to retrograde, the movement of the feed-bar is positive in both directions.

In order that the next part of my invention may be embodied in the machine, the arm k' of the counter rock-shaft P' is formed with a slot extending radially to the rock-shaft, and a block is fitted to slide in this slot. The block carries the pin i, to which the connecting-rod R' is applied, and the connecting-rod has a shifting-rod, T, fitted to it. This shifting-rod passes

up through a hole in the bed-plate A, and its upper end is formed into a screw, to which a milled nut, m, is applied, for the purpose of drawing the shifting-rod upward. The stem of the shifting-rod, beneath the bed-plate, is fitted with a helical spring, m', which, pressing against the shoulder of the rod, tends to force it and the connecting-rod R' downward.

The nut and spring, with the shifting-rod T, thus furnish a convenient means of moving the connecting-rod and the slide-block of its pin toward or from the axis of the counter rock-shaft, thereby varying the extent of movement of the pin i, and consequently the extent of movement of the feed-bar N, which receives its motion through that pin.

The feed-bar N is lifted and lowered, to seize and release the material being sewed, by means of a rocking cam, U, which is secured to the end of a rock-shaft, V, which is caused to rock at proper times by a cam, Q', secured to the driving-shaft D. This cam is triangular, like the other feed-cam, Q, and operates in a quadrangular ring, u, formed upon the upper end of a connecting-rod, X, that is applied to a crank-arm, p, projecting from the rear end of the rock-shaft V, so that the lifting-cam U is rocked by the revolution of the driving-shaft, and, from the peculiar character of the driving-cam, the lifting-cam U remains practically stationary at the end of each vibration.

The two driving-cams, Q Q', which thus operate the feed, are set at right angles to each other, or thereabouts, so that the feed-bar does not reciprocate materially when it is raised and depressed, and is not materially raised or depressed while it is reciprocated.

In order that the machine may embody the next part of my invention, the lifting-cam U is constructed with one side flat, as at r, so that it presents a flat surface for the feed-bar to slide upon, when pressed in contact with the material being sewed.

I also prefer to construct the flat surface upon a separate piece of metal, s, which is secured by a screw to the body of the cam, so that the said piece can be raised or lowered, to vary the extent of projection of the feed-bar. Moreover, as the said piece is small, it can be readily hardened, so as to present a hard wearing-surface.

The presser-foot W of the machine is of the wheel-variety, and is connected with a sliding shank, Y, to which a spring is applied, in the usual manner customary in Singer machines.

In order that the machine may embody the next part of my invention, the bearing-arm t, on which the wheel u revolves as an axle, is arranged to project from a stock, w, at the inner side of the wheel, instead of at the outer side thereof, as heretofore. This change in the arrangement brings the bearing nearer the shank Y than it otherwise would be, and consequently the pressure is more direct.

The stock w of the bearing-arm is socketed to fit on to the lower end of the shank Y, and is secured there by a screw, x, which passes through a hole made in one side of said socket; hence, by slackening the said screw the wheel-foot may be readily removed, and an ordinary plain-surfaced foot, such as represented at fig. 10, may be put in its place, to adapt the machine for work requiring such a foot.

In order that the next part of my invention may be embodied in the machine, the shank of the presser-foot is made cylindrical, and is passed through the sleeve v of a slide, Z, which extends upward into a slot in the head E' of the needle-arm, and slides therein.

Moreover, the shank Y of the presser-foot has a pin, z, projecting from one of its sides, which is received in a notch formed in the upper edge of the sleeve v of the slide.

The sleeve v is slit, and is fitted with a screw, a', to contract it, so that the friction between it and the shank

of the presser-foot can be made sufficient to cause the two to move together, but not so great as to prevent the said shank Y being turned in the slide by hand.

Hence, in the ordinary operation of the machine, the slide and shank will retain their relative positions, and the shank and presser-foot will be prevented from turning by the slide, which will reciprocate with it.

When, however, it is desirable that the presser-foot should be turned out of its position, for the purpose of changing the presser-foot, or for other purposes, the shank Y may be lifted in the sleeve, so as to disengage the pin z from its notch, and permit the shank, with the presser-foot, to be turned horizontally to any required position.

The slide Z forms a convenient means of raising the presser-foot, and, for this purpose, is constructed with a projection, d', upon which the lifting-lever C' is constructed to operate.

The machine is provided with a spooler, for the purpose of winding thread upon the spools for the shuttle. This spooler consists of a stock, D², holding a pulley-shaft, E², and a centre, F², for the end of the spool.

The shaft is constructed with a cup, g², to take one end of the spool, and with a pulley, h², covered with a belt of India rubber, m², to be pressed against and driven by the rim of the fly-wheel F.

The stock D² is pivoted to the bed-plate A, so that it may be turned on the pivot n², to cause the pulley to be driven by the fly-wheel or not.

In order that the last part of my invention may be embodied in the machine, a latch, P', is pivoted to the table B, so that it may be brought against the edge of the spooler when it is turned toward the fly-wheel, and will then hold the pulley-rim m² positively against the fly-wheel when the spooler is to be operated.

When the spooler is to be disconnected, the latch P'

is simply turned on its pivot, as represented in red lines in fig. 7, so as to release the spooler.

Having thus described a machine embodying all my improvements in the best form which I have thus far devised,

What I claim as my invention, and desire to secure by Letters Patent, is—

1. The combination of the transverse shuttle-driver, the driving-shaft of the needle, bell-crank, connecting-rods, and ball-crank pins, substantially as before set forth.

2. Also, the combination of the feed-bar with the rocking tooth which drives it, and the sliding plate which covers it, so constructed that when the sliding plate is removed, the feed-bar may be dropped into and lifted out of place with facility, substantially as described.

3. Also, the combination of the feed-bar, driving-shaft, triangular cam and connections, substantially as before set forth.

4. Also, the combination of the feed-bar, driving-shaft, triangular cam, connecting-rod, with quadrangular frame, slotted arm, and slide-pin, substantially as before set forth.

5. Also, the combination of the feed-bar and flat-sided rocking lifting-cam, rocking intermittently, substantially as before set forth.

6. Also, the combination of the presser-foot shank and guiding slide therefor, substantially as before set forth.

In testimony whereof, I have hereto set my hand, this 14th day of August, A. D. 1868.

J. T. JONES.
